United States Patent Office

Des. 222,251
Patented Oct. 12, 1971

222,251

PET COFFIN

John W. Carson, Grand Rapids, Mich., assignor to
Carson and Rogers Company, Springlake, Mich.

Filed July 13, 1970, Ser. No. 23,915

Term of patent 14 years

Int. Cl. D31

U.S. Cl. D19—1

FIG. 1.

FIG. 2.

FIG. 3.

FIG. 4.

FIG. 5.

FIG. 1 is an end, top and side elevational view of a pet coffin, showing my new design in covered position;

FIG. 2 is a top plan view;

FIG. 3 is a side elevational view;

FIG. 4 is a fragmentary end, top and side elevational view, partly in cross-section, the lid being omitted for convenience in illustration; and

FIG. 5 is a top plan view thereof with the lid omitted for convenience in illustration.

I claim:

The ornamental design for a pet coffin, substantially as shown and described.
